(57) **CLAIM**

The ornamental design for a scalloped brace pallet, as shown and described.

DESCRIPTION

FIG. 1 is an upper front perspective view of a scalloped brace pallet, showing our new design;
FIG. 2 is a lower front perspective view thereof;
FIG. 3 is an upper front perspective view thereof;
FIG. 4 is a lower front perspective view thereof;
FIG. 5 is a top view thereof;
FIG. 6 is a bottom view thereof;
FIG. 7 is a front view thereof;
FIG. 8 is a rear view thereof;
FIG. 9 is a right side view thereof; and,
FIG. 10 is a left side view thereof.

1 Claim, 6 Drawing Sheets
